ATTORNEY

UNITED STATES PATENT OFFICE

ERNEST GREGORY, OF NEW HAVEN, CONNECTICUT, ASSIGNOR TO THE LYONS MANUFACTURING CO., OF HAMDEN, CONNECTICUT, A CORPORATION OF CONNECTICUT

WHEEL SKATE OR THE LIKE

Application filed February 5, 1931. Serial No. 513,624.

This invention relates to a wheel skate or the like, having for its object, among other things, to provide a skate or device of this character that will be rigid in its structure, capable of withstanding the hard wear which its use demands, and having the minimum number of parts and so designed that the wheels thereof are always the same distance apart.

10 To these, and other ends, my invention consists in the wheel skate or the like, having certain details of construction and combinations of parts as will be hereinafter set forth and more particularly pointed out in the 15 claims.

Referring to the drawings, in which like numerals of reference designate like parts in the several figures;

Figure 1 is a plan view of my new and 20 improved skate;

Figure 2 is a sectional elevation thereof, the parts in section being taken generally upon line 2-2 of Figure 1; and

Figure 3 is a rear end view thereof.

25 In the form of skate constructed in accordance with my invention and as disclosed in the drawings; 10-10 indicates two frames which are straight for the major portion of their length and turned outwardly near their 30 rear ends to form the rear axle portions 11, and inwardly at substantially 45° near the front end at 12, and then outwardly again to form the front axle portions 13, between which is the neck portion 29.

35 These frames are the same shape on both sides of the skate and are assembled interchangeably, the front end of the frames supporting a shaft 14, upon which is rotatably mounted the front wheel 15 and the rear ends 40 supporting a shaft 16, upon which is mounted the rear wheels 17.

By this structure the shafts 14 and 16 remain in a relatively constant position. This is advantageous as it insures a rigid support, 45 minimizes the number of required parts, and the hazard of injury or damage to the parts is practically eliminated.

The proximity of the frames at the neck 29 adjacent to the rear of the front wheels 15 is a feature that also increases the rigidity

of the frames and hence the durability of the skate.

Supported on each side by the frames is a foot platform 18, provided with a slot 19 therethrough, tapered at its front end and supported by the frame portions 12, and at its rear end is formed with a heel plate 20. For convenience in positioning the heel on the skate and preventing abrasion of the shoe or foot, the upper end of the heel plate 20 is turned outwardly at 21.

Flanges 30 upon opposite sides of the frames, and parallel therewith, prevent lateral movement of the platform and insure rigidity of the parts.

Strength of the platform 18 adjacent to the heel plate 20 is increased by the corrugations 22. This platform is supported at its rear end by a truss 23 which is shaped to rest in part upon the shaft 16, the outer 70 ends 24 being turned downwardly and preferably resting upon the shaft and contacting with the inner faces of the rear axle portions 11.

This truss is preferably secured by spot 75 welding or the like to the platform 18, the shaft 16 and the frames 10, thus providing a spacing bar for the rear ends of the frames 10, a rigid support for the platform, and hold the shaft 16 against rotation.

Slidably mounted upon the platform 18 is 80 the toe plate 25, which is adjustably secured thereto by a stud 26, which passes through the slot 19, and having a wing nut 27 threaded thereon, and provided with flanges 31 upon opposite sides thereof that lie substantially parallel with flanges 31 and hold the toe plate against lateral movement. The forward end of this plate is provided with a toe clip 28 that embraces the toe of the shoe.

So far as at present advised the three-wheel skates of this character heretofore made are so constructed that the spacing between the axles of the wheels is variable as distinguished from constant, as in my improved skate. In such a structure adjustable parts are required that take the weight of the body and are subjected to strains and stresses that weaken the skate after the minimum use and this ultimately results in the 100

collapse of the skate and/or the destruction thereof.

What I claim is:

1. A skate of the character described, having two side frames that are substantially parallel with each other for a portion of their length and turned inwardly toward each other at their forward ends; a shaft supported by the frames near their forward ends; 5 a shaft supported by the frames near their rear ends; a truss that secures said frames together at their rear ends; companion wheels upon one of the shafts and a single wheel upon the other of said shafts; a foot platform on and supported by said frames; and a toe plate adjustably mounted on said platform, said truss providing a support for the platform. 70
2. A skate of the character described, having two side frames that are substantially parallel with each other for a portion of their length and turned inwardly toward each other at their forward ends and an intermediate angular portion; a shaft supported by the frames in advance of said angular portion; a shaft supported by the frames near their rear ends, said frames being formed so as to have neck portions that are adjacent to each other near said angular portions and in rear of the shaft supported by the forward ends; a truss that secures said frames together at their rear ends; companion wheels upon one of the shafts; a single wheel upon the other of said shafts; a foot platform on and supported by said frames; and a toe plate adjustably mounted on said platform, said truss providing a support for the platform. 85 25
3. A skate of the character described, having two side frames that are substantially parallel with each other for a portion of their length and turned inwardly toward each other at their forward ends and outwardly at their rear ends; a shaft supported by the frames near their forward ends; a shaft supported by the frames near their rear ends; a truss that secures said frames together at their rear ends; companion wheels upon one of the shafts and a single wheel upon the other of said shafts; a foot platform on and supported by said frames having a curved heel plate at its rear end and one or more depressions therein adjacent to said heel plate; and a toe plate adjustably mounted on said platform, said truss providing a support for the platform. 100 55
4. A skate of the character described, having two side frames that are substantially parallel with each other for a portion of their length and turned inwardly toward each other at their forward ends and outwardly at their rear ends; a shaft supported by the frames near their forward ends; a shaft supported by the frames near their rear ends; a truss between said frames, platform and the shaft, near the rear end of said frames, and permanently secured thereto; companion wheels upon one of the shafts and a single wheel upon the other of said shafts; a foot platform on and supported by said frames; and a toe plate adjustably mounted on said platform, said truss providing a support for the platform. 110 70
5. A skate of the character described having side frames; shafts associated therewith at opposite ends maintaining a constant position relatively to each other, wheels on said shafts; a platform supported by said frames; a toe plate slidably mounted upon said platform; and means for rigidly securing said toe plate in adjustable positions upon said platform. 125 75
6. A skate of the character described having side frames; shafts associated therewith at opposite ends maintaining a constant position relatively to each other; wheels on said shafts; a platform supported by said frames; a toe plate slidably mounted upon said platform; and means for rigidly securing said toe plate in adjustable positions upon said platform, said plate having downwardly projecting flanges upon opposite sides thereof and adjacent to the said frames which prevent lateral movement thereof. 135 85
7. In a skate of the character described; rigid frames; a shaft at each of the opposite ends of said frames which occupy a constant position relatively to each other; a platform to support the shoe of the user; and means for separably securing the shoe to the skate irrespective of the size thereof, said means being held against lateral movement and secured in its several adjusted positions. 140 95

In testimony whereof, I have hereunto affixed my signature.

ERNEST GREGORY.
